William J. Bole Inventor
By his Attorney, John L. Day

UNITED STATES PATENT OFFICE.

WILLIAM J. BOLE, OF PHILADELPHIA, PENNSYLVANIA, ASSIGNOR TO
JOHN A. BRILL, OF PHILADELPHIA, PENNSYLVANIA.

STREET-SPRINKLER.

SPECIFICATION forming part of Letters Patent No. 784,297, dated March 7, 1905.

Application filed September 6, 1904. Serial No. 223,545.

To all whom it may concern:

Be it known that I, WILLIAM J. BOLE, a citizen of the United States, and a resident of the city and county of Philadelphia, State of Pennsylvania, have invented certain new and useful Improvements in Street-Sprinklers, of which the following is a specification.

My improvements relate to the construction and operation of a sprinkler-head and valve whereby the size and direction of the discharged stream may be readily controlled and the opening and closing of the valve made simple and effective and also means for governing each of the above features by a single operating means.

The details of construction and further objects of my invention will appear more fully in the description and the claims hereinafter.

In the drawings forming part of this specification, Figure 1 is a perspective view of my improved sprinkler - head and controlling means. Fig. 2 is a cross-section through the sprinkler-head, showing the valve and taken on the line 2 2 of Fig. 3 looking in the direction of the arrows. Fig. 3 is a sectional view taken on the line 3 3 of Fig. 2 and showing the valve-casing. Figs. 4 and 5 are perspective views of the valve. Fig. 6 is an elevation of the valve-operating gear with the casing removed.

Similar numerals of reference designate corresponding parts throughout the various views.

My improvements are adapted for use with any kind of a sprinkling car, wagon, or any other sprinkling means with which a stream of water is directed on the roadways, and I have therefore illustrated my improvements separate from the various parts of the vehicle on which it is carried.

The valve and sprinkler-head are adapted to be secured to any of the ordinary supply-pipes, such as 1, which is fed from the tank in any desired way. At the end of the pipe I have secured a sprinkler-head and valve mechanism by a suitable threaded stem 2, which may have a nut or packing-joint formed thereon to make the parts water-tight. With-

in the sprinkler-head 3 is inclosed the operating-valve, which is secured to a spindle 4, 50 extending outwardly through the casing, in which latter it has a bearing, and a suitable support 5, which acts as a bearing for the free end of the spindle, the bearing being secured to any part of the vehicle which would give 55 it the proper position and relation to the spindle and valve.

The vertical shaft 6, which acts both as a lever and operating-shaft, is fulcrumed to a support 7, carried by the vehicle, so as to 60 pivot from the joint 8, in which latter the shaft is also adapted to rotate. Any suitable guide means, such as the eye 9, may be attached to the dashboard 10 of the car or in any desired place and is adapted to act as a 65 guide for the upper end of the shaft. An angular handle 11 of any desired shape is attached to the upper end of the shaft for the purpose of moving it longitudinally and revolving. The support 7, while it is not shown 70 as attached to any part of the vehicle, it is understood may be attached to the platform of a car or otherwise suitably secured to the vehicle which it is adapted to be used upon.

In the exact construction which I have illustrated the sprinkler-head is provided with a substantially circular casing 12, which I have provided with outwardly-extending flanges 13 to give strength and stability to the valve-casing. The interior of the casing is provided with a central bore 14, which is open at one end. The open end of the casing may be closed by any suitable means, such as a head 15, secured to the casing by any mechanical means and provided with a packed joint 16, 80 through which the spindle 4 passes and in which it is adapted to rotate and also for longitudinal movement. The interior bore 14 serves to contain a cylindrical operating-valve 17. This latter valve is so constructed as to 90 govern the direction and size of the water-discharge stream by one movement, while by a second movement it acts as a valve to immediately open or close the flow of water. For this purpose I have made the valve cy- 95 lindrical and provided it with a discharge-

opening 18 in its periphery, passing part way around it, the opening 18 communicating with the interior space of the valve and is made to flare from the interior outwardly to correspond with the flaring opening 19 in the casting, whereby the stream will be fan-shaped or flaring. Preferably on the opposite side of the valve of the opening 18 are provided openings 20, which communicate with the supply-pipe and communicate with apertures 21 in the sides of the valve, which I preferably provide therein for the purpose of allowing the water to pass into the space formed by the converging of the inner sides 22 of the valve, this space being lettered "23" in the drawings. This is not absolutely necessary, but very desirable for the purpose of equalization of pressure. The sides 22 of the valve converge toward the opening 18, so as to divert the water to the opening as it enters through the ports 20 of the opposite side of the valve-casing. I preferably provide a triangular bridge 24 in the casing, so as to give an intermediate part 25 of the valve a proper bearing and also to divert the stream through the ports 20 and into the valve. As will be understood, the valve is adapted to revolve inside of the casing, and by making the bore of the casing of greater length than the valve the latter is adapted to have a longitudinal play in the casing for the purpose of sliding the valve so as to open and close the discharge-opening 19. The movement of the valve longitudinally need only be sufficient to close the port 19. The purpose in rotating the valve is to make the opening 18 register with the opening 19 throughout its length and to govern the position of the opening so that the stream may be discharged either vertically or horizontally or may be discharged the entire length of the opening 19, as may be desired, and is controlled by the handle 11 on the spindle, as will be seen from the hereinafter description of the gear.

In order to provide a means for shifting the spindle 4 with the lever 6 and to rotate same, I have provided a pair of miter-gears, one of which, 26, is secured to the end of the shaft 6 and the other, 27, is secured on the spindle 4, so that the two mesh at the point 28. For the purpose of connecting the shaft and spindle I have provided a bracket 29, the upper part 30 of which is journaled to the end of the shaft 6, and in the sides I have provided journals 31 and 32 for receiving the spindle 4. The openings in the journal 31 and 32 are elongated slightly, so as to allow for the shifting of the spindle in the arc of the shaft 6—that is, the bracket 29 is adapted to move with the spindle 6—and by making the openings in the journal 31 and 32 elongated allowance is made for the slight circular movement of the bracket 29 in relation to the spindle 4. Any suitable casing 33 may be provided as a hous-

ing for the two gears and is preferably connected to the bracket 29.

The operation of my invention will be readily understood from the description of the construction thereof. When it is desired to open the valve, the lever 6 is thrust longitudinally, so that the opening 18 registers with the opening 19, whereupon the flow of water may pass through both. When it is desired to regulate the opening 19 so as to increase or decrease or change the direction of the stream, the handle 11 of the spindle is revolved, thereby causing the gear 26 to rotate the gear 27, and thus the spindle 4, which transmits the motion to the valve and causes the latter to rotate in either direction, whereby the water may be made to pass out at any part of the opening 19.

While many changes may be made in the construction of my new sprinkler-head without departing from the spirit of my invention, I do not desire to be understood as limiting the scope of the annexed claims by describing in details the exact construction which I have used.

Having thus described my invention, what I claim is—

1. In a street-sprinkler or similar device having a discharge-pipe, a discharge-head thereon, provided with a discharge-opening and a rotatable valve in said head, provided with an opening adapted to register with the opening in the head when said valve is revolved, and means whereby the said valve may be moved longitudinally to open the said opening in the head. 90
2. In a street-sprinkler or similar device having a discharge-pipe, a discharge-head thereon provided with a peripheral discharge-aperture, a rotatable valve in said head having an aperture adapted to register with the aperture in said head, and walls in the valve converging toward the said aperture, said valve having a receiving-opening. 100
3. In a street-sprinkler or similar device having a discharge-pipe, a cylindrical discharge-head thereon provided with a peripheral discharge-aperture, a cylindrical rotatable valve in said head having an aperture adapted to register with the aperture in said head, walls in the valve converging toward the said aperture, receiving-openings in the valve, and a bridge in said head between the said receiving-openings. 110
4. In a street-sprinkler or similar device having a discharge-pipe, a discharge-head thereon provided with a discharge-opening, a rotatable and sliding valve in said head adapted to register with the aperture in the head, a spindle on said valve and a lever adapted to independently rotate and slide said valve. 120
5. In a street-sprinkler or similar device having a discharge-head, a rotatable and sliding valve adapted to control the discharge 125

from said head, a spindle on the valve, and a lever connected to said spindle, and mounted so as to have a pivoting and revolving action, whereby the valve may be revolved or moved 5 longitudinally by said lever.

6. In a street-sprinkler or similar device having a discharge-pipe, a discharge-head thereon, a rotatable and sliding valve in the said head, a spindle on the valve, a bracket 10 in which the free end of the spindle is journaled, a gear on the spindle, a vertical lever fulcrumed to a support and adapted to revolve thereon, and provided with a gear engaging with the gear on the spindle, means 15 for holding the lever and spindle together, a longitudinal guide for the upper end of the lever and an angular handle for operating the said lever.

7. In a street-sprinkler or similar device, a 20 discharge-head thereon, a revolving and sliding valve in the head controlling the discharge therefrom, a spindle on the valve, a support

for the free end of the spindle, a vertical lever fulcrumed to a support on the sprinkler so as to pivot and revolve thereon, miter-gear 25 on the said lever and spindle, and a bracket having the said lever and spindle journaled therein, the journal of the spindle being elongated, the spindle being adapted to be revolved and moved longitudinally by said lever. 30

8. A street-sprinkler or similar device having a discharge-head having a flaring opening 19 therein, a rotating and sliding valve 23 in the head, having converging walls 22, apertures 21 in the valve, receiving-openings 20 in 35 the valve and a circular opening 18 in the valve adapted to register with the openings in the head.

Signed this 13th day of August, 1904.

WILLIAM J. BOLE.
